UNITED STATES PATENT OFFICE.

JOSEPH STEPHEN MYERS, OF SACRAMENTO, CALIFORNIA.

SHEET-MUSIC TURNER.

No. 899,459.

Specification of Letters Patent.

Patented Sept. 22, 1908.

Application filed January 25, 1908. Serial No. 412,616.

To all whom it may concern:

Be it known that I, JOSEPH S. MYERS, a citizen of the United States, residing at Sacramento, in the county of Sacramento, State of California, have invented certain new and useful Improvements in Sheet-Music Turners; and I do declare the following to be a full, clear, and exact description of the same, such as will enable others skilled in the art to which it appertains to make and use the same, reference being had to the accompanying drawings, and to the characters of referring marked thereon, which form a part of this application.

This invention relates to improvements in equipment for music stands, pianos and music holders of all kinds and particularly to devices for turning sheet music, the object of the invention being to produce a simple, inexpensive, and effective device for turning the sheet music forward and backward as required by the player and to do the same in a quick and easy manner without any danger of displacing or disarranging the sheets, and one which will readily and effectively hold the sheet in upright position at all times. This object is accomplished by means of an independent body member having a centrally disposed freely turnable vertical shaft member journaled thereon, said shaft member being provided with two outwardly projecting spring bifurcated members adapted to retain the loose leaf or sheet of the music, there being a key operated cord mechanism connected with said shaft for rotating the same backward and forward; also by such other and further construction and relative arrangement of parts as will more fully appear by a perusal of the following specification and claim.

In the drawings similar characters of reference indicate corresponding parts in the several views.

Figure 1 is a perspective view of the complete device as it appears when ready for use. Fig. 2 is a fragmentary view of a key, pulley and cord shaft operating mechanism. Fig. 3 is a bottom plan view of the complete device. Fig. 4 is a fragmentary view of an operating key mechanism. Fig. 5 is a detail view of a spring bifurcated sheet retaining member.

Referring now more particularly to the characters of reference on the drawings 1 55 represents an independent main back or

body portion of the device having a lower box portion 2 suitably inclosed by a removable cover 3.

On the member 1 within the box 2 are two journal boxes 4 spaced apart and in which is 60 journaled a freely turnable vertical shaft 5 having collars 6 for retaining said shaft in fixed vertical position in said members 4.

Slidably mounted on the shaft 5 are spaced projecting spring bifurcated members 8 65 adapted to engage and hold the loose music leaf 9.

Disposed within the box 2 are two supports 10 projecting transversely with respect to the shaft 5 and spaced apart on each side thereof, on which supports are inwardly projecting arms 11 and 12 spaced apart and holding 70 slidable pins 13, such pins having collars 14 and regulating springs 15 bearing between said collars and said members 12. 75

Held in the outer ends of the members 11 are pulleys 16, while fastened to the collars 14 is a cord 17 extending over said pulleys and wound or rove around the shaft 5 between the flanges 7. 80

The main feature of the invention is embodied in the peculiar construction of the pins 13 which are operative transversely with respect to the shaft 5, thereby working in a manner similar to the harmony keys of 85 an organ or similar instrument, which movement is the simplest and easiest of operation.

In use when it is desired to turn the sheet one of the slidable pins 13 is pushed inward causing the collar 14 to pull the cord 17 to rotate the shaft 5 by the friction thereon, which action of course turns the member 8 and music 9 as desired, and to turn it back again the other pin 13 is operated in a similar manner. 90

When a pin 13 has been depressed the corresponding spring 15 bearing on the collar 14 returns the same to normal position thereby loosening the cord 17 so that the other pin 13 may more easily operate the same when desired. 95

From the foregoing description it will be readily seen that I have produced a device for the purpose which substantially fulfills the object of the invention, as set forth herein.

While this specification sets forth in detail 105 the present and preferred construction and operation of the device, still in practice, such deviations from such detail may be resorted to as do not form a departure from the spirit 110 of the invention.

Having thus described the invention, what I claim as new and useful and desire to secure by Letters Patent is:—

A sheet music leaf turner comprising the combination of a body member having a lower box member, a pair of journal boxes spaced apart in said box a vertical shaft journaled in said boxes and having flanges bearing against the inner edges thereof, projecting bifurcated spring retaining members on said shaft, arms projecting within said box transversely with respect to said shaft and spaced apart on each side thereof, projecting

arms spaced apart on said first named arms, pins slidably disposed in said last named arm 15 transversely with respect to said shaft, collars on said pins, springs bearing between said collars and one of said last named arms, pulleys held in one pair of said arms, and a cord secured to said collars and extending 26 over said pulleys and wound around said shaft, as set forth.

JOSEPH STEPHEN MYERS.
